GAME AND PROJECTILE THEREFOR

Mitchell D. Price, Miami, Fla.

Application March 26, 1937, Serial No. 133,237

9 Claims. (Cl. 273—106.5)

This invention relates to a game of skill presenting a mild form of exercise and an abundance of amusement, and more particularly to a game embodying projectiles which are adapted 5 to be thrown or catapulted towards targets.

It is the object of the present invention to provide a game embodying a target towards which small projectiles may be directed. This game may be played either indoors or outdoors and 10 may be known as "javalina" which term may also designate the projectiles which are used, signifying small javelins.

The game may be played by throwing the projectiles by placing them flat in the hand and 15 hurling them at the target in the same manner as a knife is thrown by a knife-thrower. Further, the projectile may be cast in any other suitable way towards the target. It may further be played by catapulting the "javalinas" by 20 means of a portable catapult held in the hand or by one fixedly embedded in the ground.

It is a further object of the invention to provide a projectile, designated as a "javalina", of a proper weight and dimensions in order that the 25 same may be thrown accurately and experience a smooth flight through space. The projectile is designed to have the proper weight distribution and physical dimensions so that a mild form of exercise is obtained by its play.

30 It is a further object of the invention to provide a projectile which is rugged and capable of withstanding hard usage, and which furthermore is designed for either play by throwing or catapulting. It is also the object of the invention to provide a projectile embodying detachable heads so as to adapt the projectile to various forms of play.

Other objects and purposes will appear from a more detailed description of the invention 40 taken in conjunction with the accompanying drawing wherein,

Figure 1 is a front elevation of the game illustrating one manner of playing it,

Figure 2 is a front elevation of the projectile 45 or "javalina" in accordance with the present invention,

Figure 3 is a plan view of Figure 2,

Figure 4 is a longitudinal sectional view of Figure 3,

50 Figure 5 is a front elevation of a different embodiment of the projectile from that shown in Figure 2,

Figure 6 is a detailed sectional view of the head of the projectile shown in Figure 4 embodying a detachable head, and

Figure 7 is a sectional view of the head end of a modified form of projectile from that shown in Figure 5 embodying a detachable spherical head.

The game in accordance with the present invention is played with a plurality of projectiles 5 designated as "javalinas" which are thrown or catapulted towards a target 3 mounted upon standards 4. In Figure 1 is shown a heavy casting rod 2 having its butt end buried in the earth or set in concrete to a depth sufficient to 10 render the rod 2 secure. The portion projecting from the ground is strong and flexible and is preferably set at an angle of about 30° from the vertical, leaning towards the target. As described below the "javalinas" may be provided 15 with apertures designed to fit the top of the casting rod 2, and when the assembly is pulled back as shown in dotted lines and the "javalina" is released, it will tend to fly towards the target 20 3, and provide a test for the accuracy and skill 20 of the player. In this form of play, the exercise is derived from pulling the casting rod backwards and holding the projectile in line until the same is released. A portable casting rod held in one hand may be used in lieu of the casting 25 rod 2 embedded in the ground for the same purpose.

The projectile shown in Figure 2 may be from 30 8 to 16 inches long and preferably formed of metal. Each of these projectiles is composed of three principal parts, a head 13, a shaft portion 12 and a tail portion 11. The shaft portion 12 is in the form of a plane and the tail portion 11 is likewise in the form of a plane extending from the median line of the shaft 12 and the head 13 35 in a direction perpendicular to the shaft.

An aperture 14 is formed at the head end of the shaft portion 12 having a front wall which is substantially vertical and a rear wall which flares downwardly from the upper surface to the 40 lower surface of the shaft as shown in the drawing. This permits the "javalina" to be mounted upon the end of a casting rod as shown in Figure 1 and allows it to slide off the rod as the same is sprung from its rear position to its front 45 position along the inclined wall of the aperture.

The tail portion 11 is roughened in order to facilitate a grip on the projectile when it is used for casting by means of a catapult or else by casting it manually with the hand. Preferably 50 the projectile is held flat in the hand and is thrown at the target in the manner of a knife being thrown by a knife-thrower. The tail portion 11 is shorter but wider than the shaft portion 12 and the dimension of these two parts 55

may be apportioned so that each will have substantially the same amount of area exposed to the air. The double planes extending at right angles to each other insure a direct course, no 5 matter how the projectile is held or thrown.

The game may be played with projectiles in which the heads are pointed as shown at 13 in Figures 2 to 4 or the heads may be spherical as shown in Figure 5, oval, or of any other design.

10 In one preferred form of the construction, the end of the shaft portion 12 is threaded at 16 (Figures 6, 7) and is designed to mount detachably and interchangeably heads 13' and 15' of various weights and outlines depending upon the participants' wishes and skill.

In order to obtain the best results in the course of playing this game, the weight of the projectile is distributed so that the center of gravity thereof rests in the head and preferably at the rear 20 end thereof.

The "javalinas" may be thrown at targets of many types. These may take the form of targets shown in Figure 1 or the form of a closed frame having sounding gongs mounted thereon, as disclosed in my copending application, Serial No. 124,751, filed February 8, 1937, for "Games and exercising devices." Furthermore the projectiles can be thrown at marbles, ten-pins, or any other games which require an accurately thrown 30 missile.

While this specification sets forth in detail the present and preferred construction of the game, still in practice such deviations from such details may be resorted to as do not form a departure 35 from the spirit of the invention, as defined by the appended claims.

Having thus described my invention, what I claim as new and useful and desire to secure by Letters Patent is:

40 1. A projectile forming part of a casting game comprising a rigid plane portion having a solid head connected to one end thereof and a rigid plane tail portion connected to the other end thereof integral therewith and disposed at right angles thereto, said rigid portions and head having substantial thickness and weight.

2. A projectile for use in a game comprising a heavy head, an intermediate rigid plane section, and a rigid plane tail section at the end of said 50 first section opposite the head connected directly to the end of said first section and extending from said end in a plane perpendicular thereto at the extremity of the median line of said first section.

3. A metallic projectile forming part of a game 55 having a solid head, a rigid plane shaft of substantial thickness having one end thereof connected with said head, and a rigid plane tail of substantial thickness connected with the other end of said shaft and disposed perpendicularly thereto at the extremity of the median line of said plane shaft.

4. A metallic projectile forming a part of a game having a head, a rigid plane shaft of substantial thickness having one end thereof connected with said head, and a rigid plane tail of substantial thickness connected with the other 5 end of said shaft, disposed perpendicularly thereto and extending from the extremity of the median line of said plane shaft, said tail being wider and shorter than said shaft.

5. A metallic projectile forming part of a casting game having a solid head, a rigid plane shaft of substantial thickness having one end thereof connected with said head, and a rigid plane tail of substantial thickness connected with the other end of said shaft, disposed perpendicularly thereto and extending from the extremity of the median line of said plane shaft, said tail being roughened to permit a tight grasp thereof for the purpose of manually casting said projectile.

6. A metallic projectile having a heavy head portion, a rigid plane shaft and a rigid plane tail extending perpendicularly from said shaft from the end of the median line thereof, the center of gravity of said complete projectile being in the head, and the plane shaft and the plane tail portion connecting at right angles at the adjoining ends of their median lines and operating to stabilize the travel of said projectile through space.

7. A projectile forming part of a game having a detachable pointed head, a rigid plane shaft and a rigid plane tail extending from said shaft perpendicularly thereto from the median extremity of said shaft, the center of gravity of said complete projectile being disposed in the 35 base of the head.

8. A metallic projectile forming part of a game having a detachable spherical head, a rigid plane shaft of substantial thickness having one end thereof connected with said head, and a rigid plane tail of substantial thickness connected with the other end of said shaft, disposed perpendicularly thereto, at the function of the median lines of said plane shaft and tail, said tail being wider and shorter than said shaft and the center of gravity of said complete projectile being in the head.

9. A projectile for use in a game adapted to be cast manually or mechanically having a head portion, a plane shaft portion of substantial thickness and a plane tail portion extending from said plane shaft portion perpendicularly thereto at the median line, the center of gravity of said projectile being in the head portion, and an aperture at the forward end of said plane shaft portion in proximity to said head, said aperture having a vertical front wall and a rear wall flaring downwardly from the top to the bottom of said plane shaft portion adapted to receive the end of a flexible casting rod for impelling said projectile into space.

MITCHELL D. PRICE.
